G. W. CALDWELL,
VAPOR CABINET APPLIANCE FOR BATH TUBS,
APPLICATION FILED JULY 28, 1911.

1,089,819.

Patented Mar. 10, 1914

UNITED STATES PATENT OFFICE.

GEORGE W. CALDWELL, OF PHILADELPHIA, PENNSYLVANIA.

VAPOR-CABINET APPLIANCE FOR BATH-TUBS.

1,089,819.

Specification of Letters Patent. Patented Mar. 10, 1914.

Application filed July 28, 1911. Serial No. 640,985.

To all whom it may concern:

Be it known that I, GEORGE W. CALDWELL, a citizen of the United States, residing in the city and county of Philadelphia, State of Pennsylvania, have invented a new and useful Vapor-Cabinet Appliance for Bath-Tubs, of which the following is a specification.

My invention consists of a vapor cabinet appliance for a bath tub, the same embodying a canopy of pliable material adapted to be secured to the tub, rise therefrom and envelop the same so as to confine the vapors therein while occupied by the bather and means for adjustably sustaining and stretching the canopy in elevated and operative position.

It consists further of a bather's seat of novel construction.

It consists further of a foot supporting rack and means for suspending and containing it in the tub without liability to shift.

It consists further of means permitting the disconnecting of the rack and its appurtenances and allowing the same to be packed in compact form.

It consists further of other details of construction as will be hereinafter described.

The invention is satisfactorily illustrated in the accompanying drawing, but the important instrumentalities thereof may be varied, and so it is to be understood that the invention is not limited to the specific arrangement and organization shown and described.

Figure 1 represents a side elevation of a vapor cabinet appliance embodying my invention, including the bath tub to which the same is applied. Fig. 2 represents a perspective view of the tub and members of my appliance thereon. Fig. 3 represents a top or plan view of the parts shown in Fig. 2. Fig. 4 represents a longitudinal vertical section of a portion of the device. Fig. 5 represents a transverse vertical section of the tub-portion of the device. Fig. 6 represents a view similar to Fig. 5 with the seat omitted. Fig. 7 represents a bottom plan view of a portion of the seat. Fig. 8 represents a perspective view of an eye member to be hereafter referred to.

Similar letters of reference indicate corresponding parts in the figures.

Referring to the drawings: A designates a bath tub of usual construction.

B designates a canopy adapted to be supported on the bath tub and rise therefrom, it being formed of rubber, cloth or other suitable pliable and water proof material, 60 and somewhat pyramidal in form and having an opening in its apex for the head of the bather to protrude therethrough. The side of the canopy is provided with the flap C which may be open to permit access to 65 the interior of the canopy and consequently to the tub, and the bottom of the cabinet is formed with the hem D to receive the drawstring E, whereby when said bottom is fitted around the top of the tub and the drawstring is tightened, said bottom is contracted 70 under the rim of the same and so connected with the tub, the string being held in taut condition by the hook F on the terminal thereof, said hook engaging the eye 75 F' on the opposite portion of the canopy.

Within the tub near the bottom thereof is the foot-supporting rack G which is suspended from the top rim of the tub by means of the hangers H, whose upper ends 80 are formed with hooks J which are freely fitted on said rim, the rack being connected with the lower ends of said hangers by means of hooks and eyes K on the respective parts, said rack having also connected with 85 it the cleats L which strengthen the same and have on their ends the rubber buffers M which are adapted to abut resiliently against the adjacent sides of the tub so as to retain the rack in position without injury 90 to the tub.

N designates a seat for the bather, the same being adapted to be supported on the top rim of the tub and having on its underside at the ends thereof the grooves P which 95 are adapted to receive the top portions of the hangers H and so assist in retaining the seat in position, while also preventing shifting of the connected hangers.

Rising from the rack are the vertically extending sockets Q which receive the lower ends of the standards R each of which consist of members fitted to each other teleoscopically whereby the standards may be adjusted in height, screws or bolts S being 100 provided for holding the movable members of the standards in their adjusted position. Near the upper ends of the standards there are shoulders T, said ends being adapted to pass through the openings U in the canopy 105 below the upper end of the latter, the portions of the canopy around said walls of

said openings resting on the shoulders T by which provision the canopy may be held in set up and elevated position properly stretched.

5 Connected with the lower portion of the flap is the cord or string V which is adapted to pass through the eye W on the opposite portion of the canopy, whereby when the bather occupies the tub and canopy he is 10 enabled to close the flap after him, said cord being secured to say one of the hangers H for evident purposes. The portion of the flap above said cord V may be secured in closed condition by means of hooks and 15 eyes or eyelets shown at X in dotted lines, Fig. 1. The hangers H not engaged by the seat N may be properly held apart and stiffened by means of the brace Y which extends from one hanger to another and has 20 ends formed with bifurcations which freely engage said hangers that when the brace is forced down, it tightens against such hangers by wedge like action, thus keeping them apart and holding them tightly in position, 25 and rendering the foot rack G firm and steady in place, said hangers thus keeping the latter apart and stiffening them, as best shown in Figs. 2 and 3, the effect of which is evident.

30 In the floor of the tub is the usual outlet or drain which is occupied by the tubular stopper Z which is of such height that a limited amount of water or other fluid may be maintained in the bottom portion of the tub before being permitted to escape and vaporization of the same continued, it being noticed also that the level of the top of said stopper is such that the water or fluid will not rise above the rack G and scald or burn the feet 40 thereon. Depending from the inner side of the canopy B near the bottom thereof is the flap B' which is adapted to overhang the top rim of the tub and extend below the same so that vapor that may collect in the inner side 45 of the canopy will flow down said flap and so be directed into the tub.

When the parts are assembled, the device occupied by the bather, the canopy closed and the tub supplied with hot or medicated 50 water from any suitable source, the vapors in the tub and canopy will reach and act upon the bather producing the benefit of the same upon the latter. When the bath is accomplished, the flap is released and opened 55 when the bather may step from the tub and canopy. Afterward the draw strings may be disengaged from the eyes W F', the canopy lifted from its position, the seat and rack removed, the hangers and standards 60 removed, and the several members packed together in compact form, while the canopy may be formed into a bundle all convenient for storage and transportation. In order to 65 provide a strong support for the eyes F' and W, the same are connected with the oppo-

sitely extending bar W', the ends of which may be fitted to the proper part of the canopy and secured thereto in any suitable manner.

Having thus described my invention what 70 I claim as new and desire to secure by Letters Patent, is:—

1. In a vapor appliance for a bath tub, a foot-supporting rack within the tub near the bottom, canopy-supporting means rising 75 from said rack, a canopy removable with said rack and means for securing the same to said canopy-supporting means and around the top of the tub.

2. In a vapor appliance for a bath tub, a 80 foot-supporting rack within the tub near the bottom, canopy-supporting means rising from said rack, a canopy removable with said rack, means for securing the same to said canopy-supporting means and around 85 the top of the tub, and hangers for supporting said rack, with hook and eye connections between said rack and hangers.

3. In a vapor appliance for a bath tub, a canopy, a foot-supporting rack within the 90 tub suspended from the sides thereof, means for connecting the canopy with the tub, standards supported by said rack and removable therewith and rising above the tub, and means thereon for retaining the canopy 95 in elevated position over the tub.

4. In a vapor appliance for a bath tub, a foot-supporting rack, means for suspending the same from the sides of the tub, vertically extensible means rising from said rack and 100 means for supporting a canopy upon the upper end of said extensible means, a seat cooperating with said suspending means and means for securing the lower edge of the canopy to the tub.

5. In a vapor appliance for a bath tub, a foot-supporting rack, hangers pivotally connected with said rack for suspending the same within the tub and a seat engaging one set of hangers and co-operating therewith to 110 prevent shifting of the hangers and to retain the seat in position.

6. In a vapor appliance for a bath tub, a 115 rack, means for supporting the same therein, a canopy over said tub, means for connecting the canopy with the tub, and standards supported on and connected with said rack adapted to sustain said canopy in elevated position.

7. In a vapor appliance for a bath tub, a 120 foot-supporting rack therein, a hanger connected with said rack adapted to be suspended on the tub, and a seat on the tub over said rack, said seat having on its underside a groove which is adapted to receive the adjacent portion of said hanger.

8. In a vapor cabinet appliance for a bath tub, a foot supporting rack, hangers adapted to depend from and be freely supported on the rim of the tub, said rack being connected 130

with the lower ends of said hangers, and a brace and spreader for said hangers composed of a transversely-extending bar having its ends adapted to engage said hangers and laterally spread apart the same with a wedging action.

9. In a vapor appliance for a bath tub, a canopy, a rack in the tub, a standard rising from and secured to said rack, and a seat ¹⁵ 10 operating with the suspending means of the

rack, said standard being adapted to sustain said canopy on the tub in elevated position and being formed of members telescopically fitted to each other, the upper member being provided with a shoulder at its upper end. 15
